UNITED STATES PATENT OFFICE

JACOB A. HYLE AND EMIL R. SWANSON, OF LOS ANGELES, CALIFORNIA

RAILWAY JOINT LOCK

Application filed March 20, 1929. Serial No. 348,608.

This invention pertains to a novel and improved railway joint nut lock and is especially designed to provide a spring nut lock plate which bridges at least two bolts.

The main object of this invention is to provide simple, durable, economical, practical and thoroughly efficient means whereby the securing nuts used in connection with a railway rail joint are always locked and maintained in locked position.

The foregoing and such other objects as may appear from the ensuing description are accomplished by the construction, arrangement, location and combination of the several parts hereinafter more fully described, illustrated in the accompanying drawings and particularly pointed out in the claims appended hereto, it being understood that slight changes in the precise form, proportions and minor details of construction may be resorted to without departing from the spirit or sacrificing any of the advantages of the invention.

In the accompanying drawings forming a part of this specification it will be seen that:

Figure 1 is a top plan view showing the means embodying our invention.

Figure 2 is an enlarged side elevation of the outer face of the spring lock plate detached from the rail joint.

Figure 3 is an enlarged plan view thereof showing one end portion of the spring in section, and

Figure 4 is an enlarged plan view showing a slightly modified form of the spring lock plate shown in Figs. 2 and 3.

In the embodiment of our invention as illustrated, it will be seen that the numeral 1 indicates the track rails, 2 the rail clamping splice bars of any suitable or desirable construction, each of said bars being formed with four suitable central openings for the reception of the securing bolts 3, each bolt being passed through suitable openings formed through the track rails and said central openings of the bars, and securely fitted to the threaded end portion of each bolt is a nut 4.

The numeral 5 designates our novel spring

plate locking means which is made of high grade spring steel, preferably chrome vanadium steel, and of any suitable dimensions, such as will furnish the greatest efficiency, strength and durability, said spring plate 55 being provided with a bolt hole or opening 6 formed therethrough near each end portion, said holes being so formed that when the bolts are fitted within the holes each bolt will rest in flush contact with the plate, and 60 near each end in its outer surface is formed a depression 7 which causes a portion of the metal to flow inwardly, thus forming an inwardly extended integral portion 8, adapted to contact with the rail splice bar 2 and serving to materially increase the resiliency and the upwardly and outwardly locking tension of the spring plate when said plate is depressed into its proper locking position, as 65 shown at the right hand end portion of Fig. 1, and centrally of said plate it is formed with an outwardly extended bowed portion, forming a spring or tension member 9, for the purpose hereinafter described.

Reference now being made to Fig. 1 of the drawings it will be perceived that at the left hand side thereof the locking spring plate is shown adjusted around the locking bolts and beneath the securing nuts showing the position assumed by said plate before the 80 nuts are tightly adjusted, with a slight inclination upwardly from each end portion thereof to central spring or tension member 9, said member 9 being in its extended position at its inner end portion, while at 85 the right hand side of Fig. 1 the spring plate is shown in the position it is caused to assume when the securing nuts shall have been adjusted into their tightly locked position, said 90 adjustment thereby causing the inclined portions of the plate to be depressed.

It will be readily seen that when the secured nuts are adjusted under high pressure, the bolts that are loose in the holes of the rail joint and have a tendency to lean will straighten out, and the greater the pressure of the nuts against the spring plate the more intense the resistance and tension of the bowed portion of said plate whereby both the nuts 100

and bolts are automatically and firmly retained in a tight condition.

The spring locking plate may be formed from a single piece of spring steel of the desired dimensions, then heated and by a single operation under a suitable forge or press it is quickly and economically completed.

While all of the heads of the securing bolts are shown to be at one side of the rail joint, 10 should it be preferred to "stagger" the bolts, that is, to reverse the bolts, so that the head of one bolt of each pair of bolts is disposed on one side of the track rail, while the head of the other bolt of each pair of bolts is disposed 15 on the opposite side of said rail, it is quite evident that such a reversal of the bolts may be readily adopted with substantially the same result as has been heretofore described.

By reference to the slightly modified form 20 of spring locking plate shown in Fig. 4 of the drawings it will be seen that said plate 5' is formed with a central outward extension or tension member 9' which converges at its inner ends thus forming a contracted neck 25 portion adapted to materially increase the tension exerted by the central portion of the plate, said plate being provided with a bolt hole or opening near each end portion, and an inwardly extended integral portion 8'.

30 It will be obvious by the employment of the type of locking plate hereinbefore described, that when the securing nuts shall have been completely adjusted under high pressure all of the several parts of the rail 35 joint will be securely locked together and will be always maintained in locked condition.

Having thus described our invention what we claim and desire to secure by Letters Patent is:

1. A rail joint spring plate formed with an outwardly extended central portion, a depression at each end portion, and an integral inwardly extended portion near each end thereof.

45 2. A rail joint spring plate formed with a centrally disposed outwardly extended member, a depression formed in said plate near each end thereof, and an integral inwardly extended portion formed near each of its ends.

50 3. A rail joint spring plate formed of high grade spring steel with outwardly extended bow-shaped member, a depressed formation near each end thereof, and an integral inwardly extended portion formed adjacent each of its ends.

55 4. A rail joint spring plate formed of spring steel having a centrally outwardly extended portion, and slightly inclined from its ends toward the middle portion, a depression formed therein near each outer end, and an integral inwardly disposed extension formed near each of its ends.

60 5. A rail joint spring plate formed with a

centrally disposed outwardly extended bow-shaped member, said plate being inclined from its ends toward the middle portion, a depression formed therein near each outer end, and an integral inwardly disposed extension formed near each of its ends. 70

6. A rail joint lock comprising a spring plate, said spring plate being formed with a centrally disposed outwardly extended portion, a depression near each of its ends, and an inwardly integral extension formed at 75 each of its end portions.

7. A rail joint lock comprising a spring plate, said spring plate being formed with a centrally disposed bow-shaped member, a 80 depression formed therein near each of its ends, an integral inwardly disposed extension formed near each of its ends, and means disposed near each end of said plate for securing the plate with an extreme tensioning effect at 85 its central portion.
